UNITED STATES PATENT OFFICE.

JAMES DAWSON, OF SAN FRANCISCO, CALIFORNIA.

LIFTING-JACK.

SPECIFICATION forming part of Letters Patent No. 278,317, dated May 29, 1883.

Application filed February 5, 1883. (No model.)

To all whom it may concern:

Be it known that I, JAMES DAWSON, a citizen of the United States, residing at San Francisco, in the county of San Francisco and State of California, have invented certain new and useful Improvements in Lifting-Jacks; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in lifting-jacks, and has for its object the movement of the lifting-bar usually employed in this class of devices by means of cogs, gear-wheels, and a crank-arm, the arrangement and 20 operation of which will be more fully pointed out in the specification and claims.

Figure 1 is a side view of my improved lifting-jack, showing the side of casing, and by dotted lines the gear-wheels. Fig. 2 is a longitudinal sectional view, showing the pinions, gear-wheels, and toothed lifting-bar. Fig. 3 is a detail view of the bushings.

25 A represents a metallic shell, preferably cast rectangular in form, and having a chamber, a , of rectangular form, in its upper end, and a similar chamber, a' , in its lower end. These chambers a and a' are formed with angular apertures through their centers for the 30 passage of the lifting-bar B, and are of sufficient width and depth to admit the friction-rollers b and b' . These rollers are formed to play loosely inside the chambers a and a' , and are arranged to work against the sides of the chambers a and a' and against the sides and 35 rear of the lifting-bar B. The lifting-bar B is formed of metal, rectangular in shape, and has one edge serrated or grooved out crosswise to form teeth or cogs. The purpose of this formation, as will be more fully pointed 40 out, is to gear with cog-wheels when moved up or down through the casing A by gear-wheels and pinions.

45 Each side of the casing is perforated at two points equidistant from each other, and on the outer side of the casing A these perforations terminate in hollow projections c and c' . Inside these projections bushings d and d' are placed to form the journals or bearings for the shafts C and C'. These bushings d and d'

are formed to pass from the outer side of the 55 projections c and c' through to the inner sides of the casing A, and are held in place by set-screws e and e' . The projections c and c' are connected by stiffening-ribs f , the purpose of which is to securely hold the projections in 60 place and strengthen the sides of the casing A between the rollers or shafts C and C'. Shaft C is formed with shoulders and of sufficient length to loosely fit inside the casing A. On the center of shaft C is secured a 65 small gear-wheel, g , the purpose of which is to mesh with and operate the toothed rack-bar or lifting-bar B.

On the outer side of gear-wheel g , and near the inside of casing A, is secured on shaft C 70 a larger gear-wheel, g' .

Shaft C is formed with an angular projection on its outer end for the reception of a crank-arm or other device by which movement is communicated to said shaft. On the inside of 75 the casing A, and directly opposite wheel g' , is secured on shaft C' a small gear-wheel, h , and of sufficient size to mesh or gear with wheel g' .

The operation is as follows: Lifting-bar B is inserted through the apertures in chambers a and a' through the casing with the teeth or cogs meshing with the teeth or cogs of gear-wheel g , when power is applied to the shaft C' by means of its angular end, when the bar B is moved up or down, as desired. 85

Having thus described my invention, what I desire to secure by Letters Patent is—

1. The combination of the casing A, having chambers a and a' , holding friction-rollers b and b' , the shafts C and C', bushings d and d' , gear-wheels g , g' , and h , with the lifting-bar B, substantially as shown and specified. 90

2. A lifting-jack provided with a casing A, having chambers a and a' , containing friction-rollers against which the lifting-bar moves 95 when operated by shafts and gear-wheels, substantially as shown and specified.

3. The bushings d and d' , formed as described, and adapted to pass into the projections c and c' , and retained in place by set-screws, substantially as shown. 100

In testimony whereof I affix my signature in presence of two witnesses.

JAMES DAWSON.
